UNITED STATES PATENT OFFICE

JOSEPH H. HIGHMARK, OF DULUTH, MINNESOTA

TESTING BIT

Application filed January 6, 1930. Serial No. 418,702.

This invention relates to testing bits and has special reference to a novel form of bit for test pitting, and one particularly adapted for use in the examining of swamp lands, marshes, or the like.

The principal object is to provide a bit for effectually and easily penetrating such lands and providing means for optionally sampling from time to time the substance through 10 which the bit is passing.

Other objects and advantages of the invention will appear in the following description thereof.

The accompanying drawing, forming part 15 of this application, and wherein like reference characters indicate like parts, is an elevation partly in section, of one of the improved assembled bits.

In the drawing 1 represents the outer or 20 shell of the bit, having an enlarged ring like portion 2 spaced from the uppermost end thereof. This annular portion is pluri-faced for convenience in the application of a wrench or the like when applying or removing the 25 bit to or from the tubular casing 3 which is internally screw threaded and designed to be applied to that portion of the bit indicated at 4 which is externally screw threaded for such purpose.

30 Beneath the nut like portion 2 the bit is tapered substantially as indicated at 5, and being hollow its entire length is internally screw threaded as at 6, and the bore thus screw threaded is preferably tapered its entire length, being greater in diameter at the top than at the bottom for the reception of the externally screw threaded and similarly tapered core or plug 7.

40 The plug 7 is provided with a reduced and externally screw threaded shank 8 on the upper end thereof and which screw threaded portion of the plug is provided with a left hand thread, or at least a thread having the reverse pitch to that of the body portion of the plug.

45 The extreme lower end of the plug 7 is designed to protrude from the extreme lower rounded end of the casing or shell 1 where the plug is screwed fully home within same, and is somewhat sharpened or pointed as at

9 providing an effective terminus of the tool for easy penetration; and at 10 is represented a tubular stem or pipe for attachment to the shank of the plug for applying or removing same.

In operation the bit is firmly screwed into a piece of tubing or pipe, such as indicated at 3, when the same may be driven or forced into the earth, bog, or swamp, as the case may be, and when it becomes desirable to take a sample of the material through which the bit is passing, the driving is stopped, and a smaller tube indicated at 10 is slipped down into the tube 3 on the shank of the plug 7 and screwed up tightly thereupon. A continuation of this latter act or forcing on of said tube will result in unscrewing the plug 7, due to the reverse pitch of the thread thereupon, when the plug may be readily removed without otherwise disturbing the bit, when samples may be taken by insertion of a suitable sampling tube through the bore of the shell 1 vacated by the removal of the plug 7, and if further driving of the tube is desired, the plug 7 returned to the casing and repetition of the process resumed.

55 By such invention I have provided an exceedingly simple, efficient, and durable bit for such purpose, and one having proven in my own practice in the art of roadbuilding as being of inestimable value.

60 It will also be noted that by forming the bore of the shell 1 and the plug 7 tapered, as described, the same affords ideal conditions for the centering of the plug when inserted within the shell. That is to say requiring no special attention in meshing the threads as the plug when dropped into position within the casing is automatically centered and all 65 that is necessary is the screwing down of same into position.

65 Having thus described my invention, what I claim and desire to secure by Letters Patent, is:—

70 1. A bit of the class described comprising a hollow internally screw threaded tapered shell, and a similarly tapered and screw threaded solid plug for cooperative engagement within the shell, said plug extending 75 both above and below the shell and a reduced 80

shank integral with the upper end of said plug having external screw threads thereupon oppositely pitched to those upon the plug.

2. A two-part separable bit of the class described characterized by having tapered screw threaded cooperative surfaces throughout substantially their entire length, the innermost member of said bit having screw-threaded means of attachment to an operating rod, whereby when said rod is screwed upon said bit and further turned it will loosen same.

3. A two-part separable bit of the class described comprising an internally screw-threaded shell, an externally screw-threaded plug for cooperative engagement within the shell, said plug extending above and below the shell, and screw-threaded means upon the upper end of the plug oppositely pitched to those upon the remainder of the plug for attachment to an operating rod.

In testimony whereof I affix my signature.
JOSEPH H. HIGHMARK.
